UNITED STATES PATENT OFFICE.

JONATHAN O. FOWLER AND GEORGE W. LE COMPTE, OF NEW YORK, N. Y.; SAID
LE COMPTE ASSIGNOR TO SAID FOWLER.

CURBER FOR BRIDLE-BITS.

1,158,126.

Specification of Letters Patent.

Patented Oct. 26, 1915.

Continuation of application Serial No. 353,446, filed January 22, 1907. This application filed June 18, 1914.
Serial No. 845,803.

To all whom it may concern:

Be it known that we, JONATHAN O. FOWLER and GEORGE W. LE COMPTE, citizens of the United States of America, and residents 5 of New York, in the county and State of New York, have invented a certain new and useful Curber for Bridle-Bits, of which the following is a specification, the same being a full, clear, and exact description of the invention, such as will enable others skilled in 10 the art to which it appertains to make and use the same.

The invention relates to horse controlling devices, and in particular to a curber or controller for bridle bits, and it embodies certain novel features of construction and combination and arrangement of parts forming in operation a simple and efficient organization.

20 To attain the desired end, this, our invention, consists in the construction, arrangement and operation of novel devices and combination of devices as hereinafter set forth.

25 In order to enable the invention to be fully understood, we will proceed to explain the same by reference to the drawings, illustrative of one embodiment of the invention, which accompany and form a part of this 30 specification, and in which—

Figure 1 represents a side elevation of a horse controlling device constructed according to this invention; Fig. 2 is a plan view of the controller in connection with the 35 mouthpiece of a jointed bridle bit; and Figs. 3, 3^a and 3^b are views in detail of the end portions of the noseband.

Like letters of reference indicate like parts in all the views.

40 Referring particularly by reference characters to the drawings A denotes a jointed bridle bit and B the rein rings.

C indicates the noseband proper having at each end jaw pieces or elongated loop portions D through which the rings B are passed in attaching the noseband to the bit in the 45 operation of assembling the parts in operative relation.

The noseband which serves as a curber or 50 controller consists, in combination with a preferably resilient band C, of two preferably cast jaw pieces or elongated loop por-

tions D each ordinarily integral with a head or plate d² having a cut away portion d¹ the axis of the said loop and plate being arranged at an angle to the axis of the noseband or spring C the said plate having a shoulder d¹ from which the substantially flat and ordinarily integral thin portion d² of the plate projects. Each casting D is also 60 preferably provided with an orifice D' to which is ordinarily secured a strap E constructed and arranged to lie below the under jaw of the animal in order to prevent the horse from opening its mouth. The band C 65 ordinarily consists of thin spring metal preferably rigidly secured at each end to a plate of the casting D having its ends abutting on the shoulders d¹ of the said head or plate.

70 The castings D and the ordinarily integral heads or plates d are preferably made of non-corrosive metal by which a comparatively inexpensive and very durable construction is secured, the parts not being liable to oxidize or break under strain of the reins.

The tendency of the ordinary loop controller is to cause the horse to open its mouth in order to endeavor to release the bit by 80 dropping the under jaw and preventing the pain which is caused by the pressure of the bridle bit against the nerves of its mouth, which opening of the mouth dries it out and restricts free respiration of the animal. The 85 chin strap E will also prevent a vicious horse from getting its under jaw off to one side, as it often does with the ordinary bit—thus letting the other side of the snaffle drop too far in its mouth—and grabbing the cheek 90 of the bit with its teeth; and in all cases a horse is more easily controlled when it is prevented from opening its mouth.

We do not claim a noseband having jaw-pieces, the inner or rear ends of which are 95 inclined or project rearwardly toward the bit, broadly in this application, as the same is described and claimed in the patent to J. O. Fowler, dated Sept. 15, 1903, No. 739,163, where the inner or rear ends of the 100 jaw-pieces, whether viewed sidewise or edge-wise, are inclined inwardly or rearwardly with respect to their outer or forward ends, this application being limited to the cast

jaw-pieces having the loop and shoulder, and to a cast jaw-piece, the axis of which forms an angle with the nose band proper.

The present case is further limited to the particular details of construction hereinafter set forth. In this application, which is a continuation of an application filed by us on Nov. 26, 1906 and completed on January 22, 1907, Serial No. 353,446, it will be noted that the casting comprising each jaw-piece D having the orifice D' at its outer end is sustained in a practically pivotal relation by the bit A. Consequently, when the rein ring B connected therewith is pulled backwardly, the jaw-piece D turns somewhat on its bit pivot A and the orifice D' holding the chin strap E is pulled rearwardly and also upwardly, as the spring band C attached to the inner end of the casting D rests against the nose of the horse as a fulcrum, and the leverage thus exerted and the tightening of the said strap might, under certain conditions, cause the strap to be unduly pressed into the chin of the animal. This tendency, however, is overcome by the approach of the end of one of the jaw-pieces toward its opposite one, occasioned by the sliding of the jaw-pieces respectively upon the two members of the jointed bit A when an angular relation is assumed by the latter by a pull on the reins as is common in devices of this type. This movement serves to cause the orifices D' to come nearer together and thereby to loosen the chin strap and enable it at all times to preserve and maintain a substantially constant and uniform tension.

It will be observed that in this device the jaw-pieces have no single sharp point which might tend to obstruct the air passages of the nose and to continuously press into each cheek of the horse, and thus cause constant annoyance; nor are the jaw-pieces so nearly straight that the planes of the joints between the same and the spring and those of the ends of the spring, when in normal position, intersect the outer ends of the said jaw-pieces, which structure would cause practically the whole surface of each jaw-piece to continuously press against both the nose and the jaw, which would result, in time, in chafing the same.

We have designed the jaw-pieces so that when in normal position they shall extend for a distance in the planes of the joints between the jaw-pieces and the spring bow, and are then at the central part thereof turned outwardly to form a blunt point with a single bend at such an angle that the outer halves and ends of the same shall project a considerable distance beyond and form an angle with the said planes and also beyond the planes of the ends of the spring, and shall also be bent so that the longitudinal axis of the entire body of the same will lie 65 at a practically similar angle to the longitudi-

dinal axis of the end of the noseband. We thus secure bearing portions of greater surface than mere points, and yet not of so great a surface as to practically comprise the entire length of the jaw-pieces. By 70 means of bearing portions lying at the proper angles as hereinabove designated we are enabled to obtain at the critical moment a pressure sufficient to distract the attention of the horse and to control him without causing him unnecessary pain and annoyance which are important advantages over controllers of this type formerly employed. 75

The ease and comfort of the curber in use is also enhanced by the construction whereby the spring is bowed, or expanded, or extended outwardly from the central part thereof, and is then bent inwardly at the ends of the same—as of horizontal C-shape—the said ends being in alinement with the adjacent 85 extremities of the jaw-pieces so that the bow of the band is of a greater diameter at a distance from its ends than at the said ends. This construction of bowing the spring to press the ends of the noseband outwardly 90 against the bit-rings performs the important function of normally holding the jaw-pieces away from the jaw and thus prevents the structure from exerting any undue or unpleasant pressure against the nose and air 95 passages thereof, and also upon the cheeks of the horse (which would annoy and consequently fret him) except when the device is needed for use for purposes of correction.

We gain another important advantage in 100 making the shoulder d' so as to lie substantially at right angles to the longitudinal axis of the preferably cast jaw-piece D and to that of the head or plate d thereof which is fitted to, and engages, and is secured to the 105 beveled end of the spring. The end portions or terminals of the spring thus lap the plates and solidly abut against the shoulders of the same whereby the axis of each casting forms an angle with the longitudinal axis of the 110 spring. By this conformation of parts the casting may be more rapidly and economically made than if the said shoulder was at an acute angle to the said axis, inasmuch as all angular operations are dispensed with; 115 whereas, as the spring band C has to be cut off from a strip in suitable lengths in any event, it is just as easy to cut it off with a beveled edge as with a right angled one.

When the device is applied to a horse the 120 arch or bow of the spring and the orifices D' lying adjacent to the loops all lie rearwardly of the axis of the jointed bit, on account of the bend or drop-down between the spring and jaw-pieces. The positive turning away 125 of the jaw-pieces from the cheeks prevents the former from chafing the same as they are removed from the latter at all times except when correction is needed. In practice it has been found that the best results obtain 130

where the angle between the plane of the end of a jaw-piece and that of the end of the spring and the angle of the bend in the jaw-piece are substantially the same, as is indicated in the drawings.

We wish it to be understood that we do not desire to be limited to the exact details of construction shown and described, for obvious modifications will occur to a person skilled in the art.

What we claim as our invention is:—

1. In a device of the class described, a spring band, a plurality of jaw-pieces, and means to secure the adjacent ends thereof together, the said band being bowed and expanded so as to extend outwardly from the central part thereof and then bent inwardly at the ends of the same, as of horizontal C-shape, the said ends being in alinement with the adjacent extremities of the jaw-pieces which approach each other for a distance and at approximately the central part thereof are turned away from each other, the axis of the outer end of each jaw-piece being at an angle to the axis of each adjacent end of the spring, whereby the noseband is normally held away from, and prevented from

exerting pressure against, the nose and cheeks of the animal.

2. In a device of the class described, a spring band, a plurality of cast jaw-pieces, and means to secure the adjacent ends thereof together, the said band being bowed and expanded so as to extend outwardly from the central part thereof and then bent inwardly at the ends of the same, as of horizontal C-shape, the said ends being in alinement with the adjacent extremities of the jaw-pieces, the longitudinal axis of the entire body of each of the same lying at an angle to the longitudinal axis of the end of the noseband, whereby the noseband is normally held away from, and prevented from exerting pressure against, the nose and cheeks of the animal.

In testimony of the foregoing specification we do hereby sign the same in the city of New York, county and State of New York this 9th day of May, 1914.

JONATHAN O. FOWLER,
GEORGE W. LE COMpte.
